Fig. 2

Fig. 3

FIG. 1 is an isometric front view of a homogenizer or similar article, showing our new design.

FIG. 2 is a top plan view thereof.

FIG. 3 is a side elevational view thereof.

The undisclosed side of the motor unit is substantially the same as the side shown except for the on-off switch.

The dominant features of the design reside in the portions shown in full lines (MPEP, sec. 1503.02).

We claim:

The ornamental design for a homogenizer or similar article, as shown and described.
